UNITED STATES PATENT OFFICE.

WILLIAM A. MALONEY, OF NEEDHAM, MASSACHUSETTS.

DETACHABLE HEEL.

Application filed May 24, 1920, Serial No. 383,669. Renewed January 26, 1924.

To all whom it may concern:

Be it known that I, WILLIAM A. MALONEY, a citizen of the United States, residing at Newton, in the county of Middlesex and 5 State of Massachusetts, have invented a new and useful Detachable Heel, of which the following is a specification.

This invention relates to a detachable heel preferably of rubber or other resilient material.

Such heels have been heretofore devised to permit the wearer to readily remove and replace a worn heel when desired. It is 10 the object of my invention to provide a construction by means of which a heel may be thus removed and replaced without the use of tools or the manipulation of loose or movable parts.

Another object of my invention is to 20 provide a construction in which the inherent resilience of the heel material is utilized in securing the heel in position on the shoe.

My invention further relates to arrangements and combinations of parts which will 25 be hereinafter described and more particularly pointed out in the appended claim.

A preferred form of my invention is shown in the drawings, in which—

Fig. 1 is a partial longitudinal sectional 30 elevation of a shoe with my improvements embodied therein;

Fig. 2 is a bottom view of the permanent part of the heel;

Fig. 3 is a plan view of the detachable 35 heel;

Figs. 4 and 5 are transverse sectional elevations of the permanent and detachable parts of the heel respectively; and

Figs. 6 and 7 are perspective views of detail parts to be described.

Referring to the drawing, my improved detachable heel comprises a portion 10, permanently secured to the shoe 11 and a detachable portion or heel proper 12, preferably formed of rubber with a relatively soft lower or tread portion and a relatively hard upper portion. A headed fastening member 13 is preferably formed from sheet metal bent to the outline shown in Fig. 7, and 45 molded or otherwise permanently secured in the upper and preferably slightly concave face of the heel 12. The heel 12 is also provided with projections 14 and 15, the projections 14 being located near the front 50 corners of the heel and the projection 15 at the rear of the heel near the center thereof.

A locking plate 16 is permanently secured to the shoe and is preferably formed in a general U-shape from a single piece of sheet metal. The plate 16 is provided with a slot 60 17 enlarged at one end as clearly shown at 18 in Fig. 6. The plate 16 is preferably secured above the lower lift of the permanent heel portion 10, with the slotted portion of the plate projecting down into a 65 recess 19 in the heel lift. Elongated slots 20 are also provided in this lower lift for the projections 14 and a recess 21 is provided to receive the projection 15.

When a heel is to be attached to the shoe, 70 the projections 14 are entered in the rear ends of the slots 20 and the head of the fastening member 13 is pushed upward through the enlarged opening 18 at the end of the slot 17. The heel is then pushed 75 forward or longitudinally of the shoe until the head of the member 13 is entered in the slot 17 of the lock plate 16. During this operation, the rear portion of the heel is bent 80 outward to allow the projection 15 to slide over the face of the lower permanent lift 10 until it snaps into the recess 21, in which position it prevents relative longitudinal movement of the heel portions 10 and 12.

The projections 14 assist in holding the 85 heel in fixed lateral position on the shoe and also engage the front ends of the slots 20 to resist force exerted against the rear of the heel in a forward direction as when the heel strikes the ground in walking. The 90 lateral and longitudinal strains on the head 13 are thus substantially reduced.

The parts are thus secured without the use of tools and it will be also seen that all parts of the device are firmly secured to 95 either the heel or the shoe, there being no loose or movable parts. When the heel becomes worn, it may be quickly and easily removed by pulling the rear portion of the heel outward and then pushing the heel 100 rearward, reversing the operation previously described.

Having thus described my invention, it will be evident that changes and modifications can be made therein by those skilled in the art within the spirit and scope of my invention as set forth in the claim, and I do not wish to be otherwise limited to the details herein disclosed, but what I claim is:—

In a shoe, a heel comprising a portion 110 permanently secured to the shoe, and a resilient detachable portion, one of said parts

having a locking plate fixed in position therein, and the other part having a headed fastening member formed for locking engagement with said plate, said plate having 5 a slot closely fitting said member below the head thereof but enlarged rearward to permit free passage of said head, one of said portions having projections and the other portion having recesses to receive said projections to prevent relative lateral or longi-

tudinal movement of the parts, certain of said recesses being elongated to permit sliding, locking movement of the detachable heel relatively to the shoe and one of the recesses closely fitting its projection both laterally and longitudinally of the shoe to prevent accidental displacement of the attached heel. 15

In testimony whereof I have hereunto affixed my signature.

WILLIAM A. MALONEY.
